UNITED STATES PATENT OFFICE.

EDWIN K. CONOVER, OF PATERSON, NEW JERSEY.

DESIGN FOR A STANDARD AND CASING FOR LIFTING-JACKS.

40,874.

Specification for Design.

Patented Sept. 6, 1910.

Application filed June 6, 1910. Serial No. 565,411. Term of patent 14 years.

To all whom it may concern:

Be it known that I, EDWIN K. CONOVER, a citizen of the United States, residing at Paterson, in the county of Passaic and State of New Jersey, have invented a new, original, and ornamental Design for a Standard and Casing for a Lifting-Jack, of which the following is a specification, reference being had to the accompanying drawings, forming part thereof.

The figures of the drawing show the design of the article.

Figure 1 is a side elevation showing the full extent of the flattened side connecting

the base and the enlarged cylindrical upper portion of the article. Fig. 2 is an elevation of the article taken from a direction at right-angles to that of Fig. 1, and showing the smaller diameter of the laterally flattened standard.

I claim:

The ornamental design for a standard and casing for a lifting jack, as shown.

EDWIN K. CONOVER.
